UNITED STATES PATENT OFFICE

2,363,475

WINDOW FOR PREFABRICATED HOUSES

Claude I. Auten, Birmingham, Ala., assignor to
Tennessee Coal, Iron and Railroad Company,
a corporation of Tennessee

Original application May 3, 1943, Serial No.
485,486. Divided and this application May 11,
1943, Serial No. 486,571

3 Claims. (Cl. 20—42)

In a copending application, Serial No. 485,486, filed May 3, 1943, of which this application is a division, I have shown and described in detail the substructure and superstructure of a house whose component parts are made of cold formed sheet metal members by modern mass production methods.

One object of the present invention is to provide metal window frame elements adapted to be secured to the metal uprights of a prefabricated house such as shown in the above identified application.

Another object is to provide improved means for holding a window in various open positions of adjustment.

Another object is to construct and arrange the parts as shown and described herein so that they function individually and in combination in the manner hereinafter set forth.

For a more complete understanding of the invention, reference should be made to the following detailed description, the accompanying drawings, and the appended claims.

In the drawings:

Figure 1 is an end view of the prefabricated house having window framing and other details embodying the present invention.

Figure 2 is a vertical section on line 2—2 of Figure 1.

Figure 3 is a horizontal section on line 3—3 of Figure 1.

Referring more particularly to the drawings, 16 represents a Z-shaped sill supported on upright posts or other suitable foundation. Attached to the upper flange of the sill is a sill angle 32. A plurality of upright wall supporting members 34 are secured at their lower ends to said sill angle. At the top an eaves member 38 is secured to the upright 34, this member affording a bearing for inclined rafter members such as shown in the above identified application but forming no part of the present invention and therefore not further described herein. Between the several upright angle members 34 there are wall-enclosing panels 40 of light-gauge sheet metal having at their upright edges flanges 40^a which make face-to-face contact with the outwardly extending flanges 34^b of the upright members 34. U-shaped batten members 42 of sheet metal embrace the flanges of the uprights and wall panels, and suitable fastening bolts 36 pierce the flanges so as to hold the panels and uprights in a proper assembled condition. The present invention has particular reference to the window framing and window adjusting means to be incorporated in a

prefabricated house having the upright supporting members and wall-enclosing panels such as above referred to.

The wall construction illustrated is so arranged that stock size windows and doors can be readily installed merely by omitting one of the angular uprights so as to provide sufficient width for either a window or a door at a desired location.

At the sides of each window opening, Z-shaped 10 jamb members 81 are provided. The flanges 81^a thereof are secured to the flanges of the wall uprights 34 and the flanges 81^b of the jamb members are engaged by the screen frame later referred to. Above and below the window openings 15 the uniform spacing of the uprights 34 will continue as will also the uniform spacing of the wall panels 40, it being apparent from the drawings that the windows illustrated are of a width corresponding to that of two adjacent panels.

20 At each window location there is provided a channel-shaped window sill flashing element 84 having inner flange 84^a secured to a flange of the upright 34. This window flashing has a vertically disposed shoulder wall 84^c to which may conveniently be attached the frame 88 of a fly-screen as shown. Also attached to the sill flashing 84 is a weather strip member 90 having upwardly extended bead 92 which enters a groove formed in the lower end of the window sash 94. The window flashing 84 and weather strip 90 both span 25 the space between two uprights 34 between which the window is installed. In a similar manner, spanning the same uprights at the top of the window is a Z-shaped head member 96 whose vertical flange 96^a is bolted to the upright wall supporting member 34. The flanges 96^b of the head member extend downwardly and have secured thereto a head flashing 98 formed with a downwardly extending flange 98^a in face-to-face contact with flange 96^b of the Z-shaped head member. Suitable bolts extend through the flanges 96^b and 30 98^a so as to secure the top of the screen frame 88.

The construction and arrangement providing the upstanding shoulder 84^c and the upstanding bead 92 provides means effective to prevent rain being driven under the window, and also provides a water run-off over the screen frame and through the screen mesh. It is apparent that the upstanding shoulder 84^c will provide the inward flow of water from the substantially horizontal sill flashing 84.

The window is normally held in closed position by a turn button 100 pivotally mounted on a screw 102 passing through the flange 96^a of the head member. Near the lower extremity at each

side of the window sash is a fitting 104 to which is secured a pivot pin 106 which projects through a slot 108 formed in a respective shield plate 110 secured to the respective upright 34 at each side of the window. Each slot 108 is provided with laterally opposite notched portions 112, 114 and 116 located at successive elevations as shown in Figure 2. The shields 110 are connected with one another by a spacer bar 118. The window sash is provided with suitable sash lifts 120 of hook-like form near the top and bottom thereof. In the construction illustrated, three open positions of adjustment for the window are provided for. To open the window to the position of first adjustment, the button 100 will be turned to right angles from the position shown in Figure 2. This will permit the sash to be swung outwardly to a position wherein the pivot pin 106 will occupy the dotted position at the right extremity of the notch 112 and in this position the window will take the dotted line position indicated at 94^a. In this open position the intermediate portion of the window is supported against the spacer bar 118. When a wider window opening or more ventilation is desired, the sash will be lifted to a position in which the pivot pins 106 will occupy the notches 114 to thus adjust the window to the position indicated at 94^b. Similarly, to secure a still greater window opening and more ventilation, the position of the window can be adjusted so as to put the pivot pin 106 into contact with the extremity of the notch 116 to thus adjust the window to position indicated at dotted lines at 94^c. Thus it is apparent that the described construction provides for adequate variation of window ventilation.

While the above described embodiment of the invention has been demonstrated to be highly desirable by an actual reduction to practice on a commercial scale, it is not to be construed or limited thereto, since various modifications and substitutions of equivalents may be made by those skilled in the art without departure from the invention as defined in the appended claims.

I claim:

1. Prefabricated metal house construction comprising upright flanged wall supporting members, a metal window sill element secured to and spanning the space between a spaced pair of said members, a Z-shaped metal header secured to said members at about window height above said sill element, a window sash, upright Z-shaped sheet metal jambs coacting with the upright edges of said sash, means normally holding said sash in closed position, and means for positioning the sash in different angular open positions comprising pins secured to the sash, inwardly extended shield plates secured to said upright Z-shaped jambs and having upwardly and inwardly inclined slots therein, notches branching from said inclined slots at different elevations in which said pins are adapted to be seated, and a spacer

bar spanning the space between and secured at its ends to said shield plates, the sash being adapted to be jointly supported on said pins and said spacer bar when in any of its adjusted open positions.

2. Prefabricated metal house construction comprising upright flanged wall supporting members, flanged sheet metal panels secured to said upright members, U-shaped metal battens embracing the flanges of said panels and members, a metal window sill element secured to and spanning the space between a spaced pair of said members, a Z-shaped metal header secured to said members at about window height above said sill element, said sill element having secured thereto a weatherstrip formed with an upright bead, a window sash with a grooved bottom portion engaging said bead when in closed position, upright Z-shaped sheet metal jambs coacting with the upright edges of said sash, means normally holding said sash in closed position, and means for positioning the sash in different angular open positions comprising pins secured to the sash, shield plates secured to said upright Z-shaped jambs and having slots therein, notches branching from said slots at different elevations in which said pins are adapted to be seated, and a spacer bar spanning the space between and serving as a connecting brace for said shield plates, the sash being adapted to be jointly supported on said pins and said spacer bar when in any of its adjusted open positions.

3. Prefabricated metal house construction comprising upright flanged wall supporting members, a metal window sill element secured to and spanning the space between a spaced pair of said members, a Z-shaped metal header secured to said members at about window height above said sill element, a window sash, upright Z-shaped sheet metal jambs whose inner flanges are secured to said members and whose outer flanges and webs coact with the said sash, means normally holding said sash in closed position, and means for positioning the sash in different angular open positions, comprising pins secured to the sash, substantially triangular inwardly-extending shield plates with respective flanges secured to the inner flanges of said Z-shaped jambs, each shield plate having an upwardly and inwardly inclined slot therein, notches extended outwardly and upwardly from said slots at different elevations, said pins being adapted to be seated in said notches, and a spacer bar spanning the space between said shield plates and secured thereto adjacent the inner upper portion thereof, the sash being adapted to be jointly supported on said pins and said spacer bar when in any of its adjusted open positions, the said shield plates being effective to intercept cross drafts at the lower portion of the window opening when the sash is in open position.

CLAUDE I. AUTEN.
